UNITED STATES PATENT OFFICE.

JAMES M. WAUGH, OF CHICAGO, ILLINOIS, ASSIGNOR TO WAUGH EQUIPMENT CO., OF CHICAGO, ILLINOIS, A CORPORATION OF MAINE.

DRAFT-GEAR UNIT.

Application filed January 16, 1925, Serial No. 2,771. Renewed November 8, 1926.

Heretofore it has been the practice in furnishing draft gears for railway cars to ship the various parts comprising the draft gear unit separately, thereby making it necessary for the parts to be assembled in the 5 shops of the railway company. This practice has resulted in the making of mistakes in properly assembling the parts comprising the draft gear unit so that when assembled 10 and mounted in place between the draft sills of a car, the draft gear units failed to function properly.

In order to overcome the mistakes resulting from assembling draft gear parts in the 15 railroad shops, this invention has been devised for the express purpose of providing a draft gear unit which may be assembled by the manufacturer and shipped as a unit to the railroad companies so that the draft 20 gear unit may be readily mounted in place between the draft sills of a car without relying upon inexperienced help for the assembly of the parts forming the draft gear unit.

25 It is an object of this invention to provide an assembled draft gear unit ready for installation between the draft sills of a car.

It is also an object of this invention to provide a draft gear unit wherein the casing 30 sections forming the unit are provided with means adapted to lockingly engage the end follower blocks for the purpose of holding the assembled draft gear in operating relation ready for shipment and installation.

35 It is a further object of this invention to provide a draft gear unit which may be assembled with the draft gear friction elements disposed between the casing sections and having locking engagement therewith to afford an assembled draft gear unit.

40 It is another important object of this invention to provide a draft gear unit wherein tongues integrally formed on the casing sections are adapted to seat within notches 45 provided in the end follower plates of the draft gear unit thereby holding the casing sections locked with the friction elements to form a draft gear unit which may be shipped as a unit and readily installed between draft 50 sills of a railway car by inexperienced help or removed from between the draft sills of a railway car, as the case may be.

Other and further important objects of this invention will be apparent from the dis-

closures in the specification and the accompanying drawings.

The invention, in a preferred form, is illustrated on the drawings and hereinafter more fully described.

On the drawings:

Figure 1 is a top plan view of the draft sills of a railway car with the sill plate removed and having mounted therebetween an improved draft gear unit embodying the principles of this invention, with said draft gear unit properly disposed within the draw-bar yoke.

Figure 2 is a longitudinal sectional view taken on line II—II of Figure 1.

Figure 3 is a top plan view of the draft gear unit removed from between the railway car draft sills.

Figure 4 is an end view of the draft gear unit.

Figure 5 is a detail section taken on the line V—V of Figure 4.

Figure 6 is a side elevation of the draft gear unit.

Figure 7 is a fragmentary end view of a modified form of follower plate with parts 80 broken away and having a modified form of locking lug engaged therewith.

Figure 8 is a reduced fragmentary detail section taken on line VIII—VIII of Figure 7.

As shown on the drawings:

The reference numeral 1 indicates a pair of railway car draft sills of channel iron construction which are mounted longitudinally on the car. A sill plate 2 (Figure 2) is 90 mounted on and connects the upper flanges of the draft sills. Removably secured to the lower flanges of the draft sills 1 by means of bolts or other suitable means is a transversely disposed carry iron 4, the ends of which are 95 bent to form flanges which project upwardly beyond the lower sill flanges. The carry iron 4 is constructed to afford a support and guide for the draft gear mechanism as hereafter described.

Secured to the inner face of each of the draft sills are front and rear stop blocks or castings 5 and 6 respectively and which are riveted or otherwise secured to the sills and are positioned to the front and rear 105 respectively of the carry iron 4 to afford a space between which the draft gear unit of this invention is adapted to fit. The stop

castings 5 and 6 are provided with inwardly directed flanges which serve as stops or abutments for the casing sections of the draft gear unit.

- 5 Supported in the end of the railway car upon a transverse guide beam 7 is a coupler or drawbar 8 to the inner end of which is removably secured by bolts or other suitable means a yoke 9. The yoke 9 is provided to 10 engage around or hold the draft gear unit in place as illustrated in Figures 1 and 2 of the drawings.

Shocks or other stresses imparted to the drawbar 8 and the yoke 9 are transmitted 15 to the draft gear unit and absorbed by the friction elements therein before being transmitted to the draft sills and other parts of the railway car. The improved draft gear unit embodying the principles of this invention are clearly illustrated in Figures 3 to 6 inclusive and comprise a pair of casing or housing sections which are constructed alike. Each of the draft gear casing sections comprises a metal casting 10 having a raised integral middle portion or boss 11 formed with a middle opening or recess 12 as shown in Figure 3. Each end of each of the casing sections 10 is provided with a notch or recess 22. Integrally formed 20 along the longitudinal edges or sides of each of the casing sections 10 are side plates or flanges 13. Integrally formed on each end of each of the casing side plates or side flanges 13 are inwardly directed locking 25 lugs or tongues 14.

The shock absorbing elements forming a part of the draft gear unit are adapted to be carried between the two casing sections and comprise a series of groups of friction plates 15; with the plates in each group placed face to face and adapted to be collectively bowed or bent by either thrusting or pulling strains applied to the coupler or drawbar 8. The two middle groups of friction plates 15 are separated by a double convex spacer block 16. The outer groups of friction plates are separated by double concave spacer blocks 17. Positioned against the outer friction plate of each end group of plates is the convex inner face 18 of a follower block 19. Each follower block 19 has formed thereon upwardly and downwardly projecting lugs or shoes 20 which project through the recesses 22 of the casing sections. The flat outer face of each of the follower blocks 19 is provided with a plurality of recesses or notches 21 as clearly illustrated in Figures 4 and 5. The notches 21 are provided in the follower blocks for 40 the purpose of receiving the latching or locking lugs 14 which are integrally formed on the casing sections 11. The lugs 14 when engaged in the notches 21 of the follower blocks serve to afford a locking arrangement 45 whereby the casing sections may be locked

with the follower blocks thereby providing a compact draft gear unit which may be readily assembled by the manufacturer and shipped as a unit to railway car builders to be placed in position in railway cars without requiring expert assemblers.

As illustrated in Figure 5 the various groups of friction plates 15 together with the follower blocks 19 and the separators 16 and 17 are grouped as illustrated in Figure 5 and compressed by any suitable means so that the group of friction elements may be placed within the lower casing section 10 after which the upper casing section may be placed in position to enclose the upper portions of said friction elements. The compressing device is then removed from the friction elements thereby permitting the springs to exert an outward force on the follower blocks, thereby pushing said follower blocks into a position to permit the notches 21 thereof to lockingly receive or engage the locking lugs 14 which are integrally formed on the ends of the side flanges 13 of the casing sections 10. The friction elements and the casing sections thus are assembled to afford a compact draft gear unit which may be readily handled and after being assembled by the manufacturer may be shipped as a unit to the railway companies to be installed as a unit in the drawbar yokes 9 as illustrated in Figures 1 and 2 of the drawings.

Figures 7 and 8 illustrate a modified form of locking arrangement between a follower block 23 and curved hook members 24. The follower block 23 is provided with recesses 25 forming lugs or beads 26 over which the hooks 24 are adapted to engage. The hooks 24 are integrally formed on the ends of the side plates or flanges 13 of the casing sections 10 to permit the parts of a draft gear to be held in assembled relation to form a draft gear unit.

I am aware that numerous details of construction may be varied through a wide range without departing from the principles of this invention and I therefore do not purpose limiting the patent granted hereon, otherwise than necessitated by the prior art.

I claim as my invention:

1. The combination with a pair of railway draft sills, of a carry iron connecting said draft sills, a plurality of stop blocks secured to said draft sills, a drawbar, a yoke thereon, a plurality of casing sections positioned in said yoke, friction elements between said casing sections, notched follower blocks between said casing sections and separated by said friction elements, and locking lugs integrally formed on said casing sections for engagement in the follower block notches for locking said casing sections, with said follower blocks to form a draft gear unit.

2. The combination with a pair of railway car draft sills, of stops mounted thereon, a carry iron connecting said draft sills, a drawbar, a yoke on said drawbar supported on said carry iron, casing sections disposed in said yoke between said stops, friction elements mounted between said casing sections, follower blocks forming a part of said friction elements and having notches therein, and locking lugs integrally formed on said casing sections adapted to be seated in the follower block notches to form a draft gear unit comprising said casing sections and friction elements.
3. The combination with a drawbar and yoke, of a draft gear unit comprising a casing, notched follower blocks in the said casing, friction elements in said casing disposed between said notched follower blocks, and locking members integrally formed on said casing adapted to lockingly engage the said notched follower blocks.
4. A draft gear unit comprising a pair of casing sections, a plurality of groups of shock absorbing plates positioned between said casing sections, separator blocks between said casing sections separating said groups of shock absorbing plates, notched follower blocks between said casing sections and positioned to the outside of the end groups of said shock absorbing plates, and projections formed on said casing sections adapted to seat in the notches of the said follower blocks.
5. A draft gear unit comprising a pair of notched casing sections, locking projections integrally formed on said casing sections, a plurality of groups of friction plates positioned between said casing sections, a double convex spacer block between said casing sections separating the two middle groups of friction plates, a plurality of double concave separator blocks separating other of said groups of friction plates, and convex follower blocks positioned to the outside of the outermost of the friction plates and projecting into the notches of said casing sections, said convex follower blocks having notches therein to receive the locking projections of said casing sections.
6. A draft gear unit comprising a casing having locking members formed thereon, followers movably positioned in said casing and having notches therein for receiving said locking members seated therein, and friction elements in said casing separating said followers and acting to hold said followers in locking engagement with the locking members of said casing.
7. Draft gear structures comprising follower blocks, spring plates disposed between said blocks, channel-like cover members disposed against opposite edges of said blocks and spring plates, and releasable lost motion connection between said cover members and said follower blocks for maintaining all of said parts in assembled relation.

In testimony whereof I have hereunto subscribed my name.

JAMES M. WAUGH.
